CARTON OPENER

Joseph E. Kroemer, St. Paul, Minn.

Application January 13, 1939, Serial No. 250,721

5 Claims. (Cl. 30—2)

My invention relates to carton openers and has for an object to provide an opener having a cutting blade and in further providing a guard therefor adapted to be moved from guarding to unguarding position.

Another object of the invention resides in utilizing with the carton opening device a razor blade and in constructing the end of the edge of the body with which the razor blade is associated receding from the outermost portion thereof and in arranging said razor blade to extend outwardly from the receding portion of the edge of said body.

A feature of the invention resides in constructing the body with two plate-like body members overlying one another and in disposing the blade in between said body member and in further providing a bolt extending jointly through said plate-like body members for clamping the same together.

Another object of the invention resides in employing a plate-like guard disposed between said body members and lying adjacent said blade and in providing said guard with an opening through which the bolt extends and by means of which the guard is pivoted.

A still further object of the invention resides in constructing the body with a lug adapted to hold the blade from rotation and in providing the guard with a slot through which the lug extends and by means of which the movement of the guard is limited.

An object of the invention resides in arranging said slot so that the guard may move from a position completely covering the exposed edge of the blade to a retracted position in which the exposed portion of the blade is available for use and to other intermediate positions.

Another object of the invention resides in constructing the guard with an edge providing a gauge surface for limiting the depth of cut of the blade when the guard is in one of its intermediate positions.

A feature of the invention resides in constructing the guard with a notch, forming thereon a finger piece by means of which the same may be manipulated.

Other objects of the invention reside in the novel combination and arrangement of parts and in the details of construction hereinafter illustrated and/or described.

In the drawing:

Fig. 1 is a perspective view of a carton and bottle opener showing the guard in guarding position.

Fig. 2 is a longitudinal sectional view taken on line 2—2 of Fig. 1 and drawn to a greater scale.

Fig. 3 is a longitudinal sectional view taken on line 3—3 of Fig. 2 and turned around.

Fig. 4 is an elevational view of the opener showing the guard retracted and illustrating the method of using the invention for making a full depth cut.

Fig. 5 is a view similar to Fig. 4 showing the guard in position for limiting the depth of cut of the blade.

Fig. 6 is a cross sectional view taken on line 6—6 of Fig. 2.

My invention comprises a body 10 which is provided with two plate-like body members 11 and 12 preferably stamped from sheet metal. Both of these body members are of the same form excepting that one is right hand and the other is left hand and when the said body members are assembled the edges of the same register with one another and give the desired outline to the body proper. The body 10 carries a carton opening device 13 and a bottle opening device 14 which will now be described in detail.

The body 10 is constructed with two longitudinally extending spaced parallel edges 15 and 16. The edge 16 is bent back and receded, as indicated at 18, which formation is disposed at one end of the said edge. The opposite edge 15 of the body, at the same end, is rounded as designated at 19. The opposite end of the body 10 is provided with a head 21 and the edge 16 is curved at 22 to partly form the said head.

The bottle opening device 14 comprises a hook 23 which is formed by removing a portion of the metal of both of the body members 10 and 11 to provide an opening 24 accessible from the edge 15 of the body 10. The head 21 extends out to substantially the width of the body as limited by the edges 15 and 16 and serves to guard the hook 23. Hook 23 is also disposed inwardly of the edge 15 so that the same is further guarded. The portion 29 of the head 21 serves as a fulcrum for giving the leverage in the use of the hook 23.

The carton opening device 13 utilizes a safety razor blade 25 which is disposed between the two plate-like body members 11 and 12. This safety razor blade has a cutting edge 26 and is so disposed that a portion 27 of said cutting edge projects outwardly beyond the portion 18 of the edge 16 of body 10. The said blade and the two body members 11 and 12 are held in assembled position in the following manner: Issuing out-

wardly from the inner surface of the body member 12 are three lugs 28, 29 and 30 which register with three depressions 31, 32 and 33 formed in the inner surface of the body member 11. The lugs 29 and 30 extend through openings 34 and 35 in the razor blade 25 and hold the said blade from movement. Extending jointly through the two body members 11 and 12 is a bolt 36 which also passes through the center hole 37 in the razor blade 25. A wing nut 38 screwed upon the end of this bolt serves to clamp the parts in position and by means of the lugs 29 and 30, the razor blade 25 is held from movement. When properly positioned, the end of the razor blade is disposed near the end of the body 10 and the portion 27 of the cutting edge 26 thereof projects outwardly from the portion 18 of the edge 16 of said body.

In conjunction with the carton opening device 13, a guard 39 is employed. This guard is constructed in the form of a plate-like member preferably stamped from sheet metal and is disposed between the two body members 11 and 12 and adjacent the razor blade 25. Bolt 36 passes through this guard and the said guard becomes pivotally mounted thereon when the wing nut 38 is loosened. Guard 39 is constructed with a portion 41 which is adapted to be moved to a position such as shown in Fig. 3 in which the said guard covers the exposed portion 27 of the cutting edge 26 of blade 25. The said guard may be moved to its opposite position as shown in Fig. 4 where the guard is fully receded and the exposed portion of the blade 25 arranged for use. To facilitate and limit movement of the guard 39, the same is constructed with an arcuate slot 42 through which the lug 30 extends. This slot is constructed concentric with the axis of the bolt 36 and is of such a length that the lug 30 terminates movement of the guard when in its two extreme positions, as shown in Fig. 3 and Fig. 4. The guard 39 is constructed at its end with a notch 43 which forms in the guard a finger piece 44 which projects outwardly beyond the curved edge 19 of body 10 and by means of which the guard may be moved from one position to the other. The guard 39 has an edge 45 which extends in the same general direction as the edge 26 of the blade 25 and which, when the guard is moved to an intermediate position as shown in Fig. 5, provides a gauge surface for limiting the depth of the cut made by the carton opening device.

In order to more readily manipulate the carton opening device, two wings 46 and 47 are formed on the body members 11 and 12 which wings are bent out therefrom and lie along the portions 18 of the edge 16 of body 10. Pressure may be applied to the blade 25 by the thumb and fore-finger of the user and through the wings 46 and 47 while the device is grasped by the hand with the remaining fingers engaging the portion 22 of the edge 16 of body 10.

The use of the invention is as follows: When the device is to be used for cutting the full depth, guard 39 is arranged as shown in Fig. 4 and the nut 38 tightened up to clamp the parts in position. The opener is grasped, as previously explained, between the thumb and fore-finger, the said thumb and fore-finger resting upon the wings 46 and 47. At the same time the remaining fingers extend beneath the edge 16 of the body 10 and particularly the portion 22 thereof. Blade 25 is then forced through the wall of the carton to be opened which in Fig. 4 is des-

ignated by the reference numeral 48. The opener is then drawn longitudinally and the wall 48 cut in a simple and expeditious manner. In certain cartons it becomes desirable to only cut through the first thickness of the wall to be opened. In Fig. 5 the opener has been shown as adjusted for this purpose. In this figure the wall of the carton is illustrated as having two thicknesses of material 51 and 52. In the particular instance it is desirable to only cut through the thickness 51. Toward this end guard 39 is so adjusted that the edge 45 thereof engages the upper surface of the thickness 51 when the blade 25 penetrates the said thickness. When the guard 39 is in proper position the wing nut 38 is screwed down and the parts rigidly held in the desired position. If the opener be now manipulated in the same manner as previously described, the upper thickness 51 only of the carton wall is cut. When the carton opening device is no longer needed the guard 39 is moved to the position shown in Fig. 3 and no injury to the user will result.

After the carton has been opened and it becomes desirable to open the bottles contained therein, the body 10 is reversed, as shown in Fig. 1, and the hook 23 placed beneath the crown cap of the bottle with the portion 49 of the head 21 serving as a fulcrum or resting against the upper surface of the crown cap. The device is grasped by placing the fingers beneath the portion of the edge 15 between the hook 23 and the curved end 19 of body 10 and by placing the thumb upon the portion 22 of the edge 16. The device is then manipulated in the customary manner.

The advantages of my invention are manifest. An extremely simple and practical construction is provided which efficiently and effectively serves the desired purpose. My invention may be used both to open the cartons in which bottles are contained, as well as removing crown caps from bottles. My improved carton opener may be readily constructed from stampings and at a nominal cost. With my invention the cutting blade may be completely guarded so that injury to the user is prevented. Also the guard may be used as a gauge for determining the depth of the cut. The parts are arranged so that the carton opening device and the bottle opening device are disposed at opposite ends of the body and accessible from opposite sides of the body of the invention. In this manner the diagonally opposite portions of the opposed edges of the body serve as finger pieces for engagement with the fingers of the user. In this manner each device is out of the way when the other is being used. My invention is extremely compact and occupies a minimum amount of space.

Changes in the specific form of my invention, as herein disclosed, may be made within the scope of what is claimed without departing from the spirit of my invention.

Having described my invention, what I claim as new and desire to protect by Letters Patent is:

1. In combination, a body comprising a plate-like body member, a second plate-like body member overlying the first plate-like body member, a cutting blade disposed between said plate-like body members, said cutting blade having a cutting edge fixed relative to said body and a plate-like guard overlying said cutting blade and disposed between said plate-like body members, a bolt extending jointly through said body members, blade and guard, said guard being pivoted

on said bolt and being adapted to be moved in a direction such that one edge thereof travels toward and from said cutting edge, said guard being movable from a position guarding said exposed cutting edge to positions partly exposing said cutting edge whereby the edge of said guard engages the object cut and limits the depth of the cut made by said cutting edge.

2. In combination, a body comprising a plate-like body member, a second plate-like body member overlying the first plate-like body member, a cutting blade having two spaced openings therein and disposed between said plate-like body members, a plate-like guard over-lying said cutting blade and disposed between said plate-like body members, a bolt extending jointly through said body members and guard and through one of the openings in said blade, said guard being pivoted on said bolt, one of said body members having a raised portion adapted to be received within the other of the openings in said cutting blade and the other of said body members having a depression in which said raised portion is received whereby the cutting blade is held from rotation, said guard having an arcuate slot through which said raised portion extends, said slot limiting movement of said guard from a position guarding said cutting blade to a retracted position.

3. In combination, a body comprising a plate-like body member, a second plate-like body member overlying the first plate-like body member, a cutting blade having two spaced openings therein and disposed between said plate-like body members, a plate-like guard over-lying said cutting blade and disposed between said plate-like body members, a bolt extending jointly through said body members and guard and through one of the openings in said blade, said guard being pivoted on said bolt, engaging means carried by one of said body members and adapted to engage said blade within the other opening thereof, said

guard having an arcuate slot through which said engaging means extends, said slot limiting movement of said guard from a position guarding said cutting blade to a retracted position.

5. In combination, a body comprising a plate-like body member, a second plate-like body member overlying the first plate-like body member, a cutting blade having two spaced openings therein and disposed between said plate-like body members, a plate-like guard over-lying said cutting blade and disposed between said plate-like body members, a bolt extending jointly through said body members and guard and through one of the openings in said blade, said guard being pivoted on said bolt, engaging means carried by one of said body members and adapted to engage said blade within the other opening thereof, said guard having a portion extending outwardly beyond the end of the blade, and a finger notch formed in said portion of the guard and being disposed entirely beyond the end of the blade.

10 5. In combination, a body comprising an elongated plate-like body member, a second elongated plate-like body member overlying the first body member, said body members having spaced 25 longitudinal edges, a cutting blade fixed relative to said body and having an elongated cutting edge and a back edge said cutting edge being disposed between said body members with a portion 30 of the cutting edge disposed inwardly of one of the longitudinal edges and with another portion exposed by one of said longitudinal edges, a guard pivoted to said body members, said guard having a guage surface facing in the same direction as the exposed portion of said cutting edge, said guard being movable in a direction toward the back edge of the blade to vary the distance 35 between the cutting edge and guage surface, and means for clamping the guard and blade relative to one another and to said body members in any 40 of its adjusted positions.

JOSEPH E. KROEMER.
